Patented Nov. 4, 1958

183,841

GAME BOARD

Charles B. Keats, Fairfield, Conn.

Application April 23, 1958, Serial No. 50,592

Term of patent 14 years

(Cl. D34—5)

Fig. 1

Fig. 2

Fig. 3

Fig. 4

Figure 1 is a top plan view of a game board embodying my design.

Fig. 2 is a front elevational view of the game board of Fig. 1.

Fig. 3 is a side elevational view of the game board.

Fig. 4 is a rear elevational view of the game board.

I claim:

The ornamental design for a game board, as shown.
